UNITED STATES PATENT OFFICE.

BENJAMIN L. FREY, OF ST. LOUIS, MISSOURI, ASSIGNOR TO NATIONAL SALES MACHINE COMPANY, OF ST. LOUIS, MISSOURI, A CORPORATION OF MISSOURI.

COIN-CONTROLLED VENDING MACHINE.

Application filed March 3, 1926, Serial No. 92,062. Renewed November 2, 1927.

This invention relates to coin controlled vending machines and more particularly to improved means for conducting the deposited coins, if of proper denomination, to the trip device of such machine to actuate the same to provide for delivery of the commodity paid for, and otherwise dispose of such deposited coins as are not of proper denomination and in a manner to prevent actuation of the trip device thereby.

One of the important objects of the invention is to provide novel means for automatically and positively directing the path of travel of the coins as to insure of deflection of a coin not of proper denomination from the path of travel of a coin of the proper denomination in a manner to insure against any contact of a coin such as that first mentioned with the trip of the delivery mechanism, and to accomplish this object without in any way impeding the travel of the coin regardless of its denomination, so that there can be no clogging of the coin passages.

The mechanism embodying the invention is designed primarily for installation in coin controlled vending machines of that class constructed for vending various commodities of various kinds of the same commodity which have different selling prices and which machines are so constructed that, in order to effect delivery of any one commodity therefrom, coins of different denominations must be deposited, and inasmuch as certain car tokens and bus tokens are of diameters approximating the diameters of coins of different denominations, the invention has as a further object to provide for the collection of such tokens, where they are deposited with fraudulent intent, without liability of actuation of the trip mechanism of the machine, instead of returning such deposited tokens to a place where they might be recovered by the depositor.

Another important object of the invention is to so construct the coin conducting means that where the same is adapted to receive a coin of proper denomination and, therefore, having predetermined dimensions, the deposition of a coin, token, or the like, of smaller dimensions, will not result in clogging of the coin passages which might otherwise result from marginal overlapping of two deposited coins of the character stated.

Another object of the invention is to so construct the coin conducting means that if, through error or intent, two or more coins of the same denomination should be deposited, clogging of the coin passages will not result, and in this respect the invention presents a decided advantage where embodied in coin controlled vending machines of the type referred to, in which coins of different denominations must be deposited in the coin slots of a unit of the machine before complete actuation of the trip mechanism to deliver the commodity, for in this event it will still be necessary to deposit a coin of the other required and proper denomination to actuate the said trip mechanism and yet all deposited coins will be delivered into the coin receptacle.

As previously stated, the mechanism of the present invention is designed for installation in a vending machine from which various commodities are to be dispensed and it is another object of the present invention to so construct the mechanism embodying the same that it will constitute a unitary structure adapting it to be not only readily installed but likewise adapting one unit to be substituted for another.

Another object of the invention is to provide for the automatic deflection of coins not of the proper denomination, from the path of travel of coins of proper denomination, through gravity, thereby obviating the necessity of employing any mechanically operating ejecting or deflecting means for accomplishing this result.

In the accompanying drawings:

Figure 1 is a vertical front to rear sectional view through a vending machine in which the mechanism of the present invention is installed, the mechanism of the invention being shown in elevation and a coin being likewise shown in the said figure at several points in its travel.

Figure 2 is a detail view in side elevation of the mechanism embodying the invention, the adjacent side plate being removed to more clearly illustrate the passageway for the coins.

Figure 3 is a vertical transverse sectional view taken substantially on the line 3-3 of Figure 2, looking in the direction indicated by the arrows, the side plates being in position.

Figure 4 is a horizontal sectional view on the line 4—4 of Figure 2, looking in the direction indicated by the arrows.

Figure 5 is a group perspective view illustrating a portion of one of the units of the present invention and the coin chute and another part associated therewith.

Figure 6 is a perspective view of the side plate which is designed for application to the outer side of the section shown in Figure 5.

As before explained, the mechanism embodying the invention is constructed as a unit and a number of the units are to be built into the casing and base of a vending machine of the type heretofore referred, although it will be understood that, in smaller sizes, the machine as a whole may embody only one of said units.

- 20 In the drawings, the particular cabinet structure illustrated comprises, in addition to the usual side walls, (not shown), a back 1, a front 2, a top 3, and a base indicated in general by the numeral 4 and comprising a top 5, ends 6, a back 7, an open front 8, and a longitudinal support 9 which is arranged within the interior of the base and which includes a downwardly and forwardly extending bottom portion 10 extending to the open front 8 of the base and upon which the commodities are deposited, and a similar bottom portion 11 which extends downwardly and rearwardly and constitutes the bottom of the coin receptacle of the machine, this being closed at its rear by the said back 7 which is preferably hinged so that authorized access may be had to the said receptacle. The back 1 and front 2 are supported upon the top 5 of the base 4 and the units embodying the invention and which are indicated in general by the numeral 12, are supported upon the support 9, as best shown in Figure 1 of the drawings. The casing is divided interiorly by vertically extending partition walls 13, into storage compartments 14, in which the commodities to be dispensed are contained and, of course, these compartments will be so proportioned as to accommodate the particular commodities, which may be packages of cigarettes, cigars, packaged proprietary remedies, and, in fact, any and all articles of commerce which are adapted to be dispensed by a vending machine.
- 25 Each of the units 12 comprises spaced parallel upright side members 15 and a bottom or base 16 which extends between the lower ends of the side members and is integral therewith, the bottom 16 being secured upon the supporting member 9 and the side members 15 extending upwardly between the front 2 and back 1, as clearly shown in Figure 1. The unit is open at its front and rear, and as will be observed by reference to Figures 3 and 5 of the draw-

ings, the walls 13 of the associated commodity storage compartments 14 extend vertically from the side walls 15, the side walls 15 being preferably provided at their upper edges with longitudinally extending grooves indicated by the numeral 17 and the groove of each side member accommodating an offset flange 18 at the lower end of the respective wall 13 so that the units may be separated from their respective walls 13 and likewise readily assembled therewith.

The numeral 19 indicates in general the commodity ejecting device of the mechanism and the same comprises, as usual, a substantially oblong rectangular frame including side members 20, a front 21, and a back 22, the forward portion of the frame being open at its top, as indicated by the numeral 23, so as to receive and retain, until the time of delivery, one of the commodities to be dispensed such, for example, as a package of cigarettes, this portion of the frame being, as usual, of dimensions to more or less exactly receive the said commodity. The rear or remaining portion of the frame is closed or substantially closed at its top, as indicated by the numeral 24, so that, the frame being slidably disposed upon the bottom 16, the closed top 24 will slide beneath the lowermost one of the commodities stored within the compartment 14 as the member 19 is slid forwardly, to deliver the commodity onto the bottom portion 10 of the base 4, and thus support the stack of commodities until the member 19 has been returned to its normal position, whereupon the lowermost one of the stack of commodities will automatically drop into the open forward portion of the frame of the said member. The usual stem, indicated by the numeral 25, is connected with the front 21 of the frame and works through an opening 26 in a depending portion of the top 5 of the base at the front thereof, a spring 27 being arranged as usual upon the said stem and bearing between the said portion of the top of the base and the said front of the ejector member 19, so as to normally hold the member at the rearward limit of its movement, the stem being provided with the usual knob 28 which may be grasped for the purpose of shifting or sliding the member 19 forwardly when proper coins have been deposited to provide for release of the said member for such movement. This construction is not a part of the present invention but the invention contemplates forming longitudinal recesses 29 in the opposing faces of the side members 15 of the unit 12 immediately above the plane of the bottom 16, which recesses are of a depth substantially equal to the height of the frame of the ejector member so that the upper edges of the sides 20 of the said member will ride beneath the upper wall or shoulder 30 of

the recess and the ejector member thus steadied in its movement and prevented from upward displacement. Likewise, when the member is in normal position, the 5 forward portions of the sides of the frame comprising said member will be received substantially flush within the respective recesses 29.

In accordance with the principles of the 10 invention, any detent or latching device may be employed for holding the ejector member 19 against forward sliding movement until released automatically through the deposition of coins of proper denomination, but to 15 represent an operative structure, a detent device such as shown in Figures 2 and 3 of the drawings, may be employed. This device comprises a trip 31 which is mounted intermediate its ends for rocking movement upon 20 a pivot stud 32 which projects outwardly from the respective side member 15 of the unit 12, the outer face of the side member being recessed as at 33 to accommodate the 25 said trip, it being understood that the detent mechanism is duplicated at the opposite side of the unit, and that the construction and arrangement of the parts at each side of the unit is identical. The rear end of the trip 31, indicated by the numeral 34, extends immediately below the delivery end 35 of a 30 coin passageway which is indicated in general by the numeral 36 and which is formed in part by recessing the outer face of the respective side member 15 and by a face plate, indicated in general by the numeral 37, which is removably secured in place against the outer face of the respective side member 15. A longitudinal slot 38 is formed in each side member 15 and opens through the front 40 vertical edge thereof, and a boss 39 is formed upon each side member of the frame of the ejector member 19 and carries a stud 40 which coacts with the detent in a manner which will now be briefly explained, the 45 boss working in the said slot 38. The detent forwardly of its pivot 32 has spaced upper and lower fingers 41 and 42, the finger 41 constituting a latch finger and having a fixed tooth 43 at its forward end projecting down- 50 wardly toward the finger 42, and a latch element 44 being pivoted, as at 45, upon the forward end of the finger 41 and having a depending tooth 46 at its rear or free end. The stud 40 works between the fingers 41 and 55 42 and it will be evident by reference to Figure 2 of the drawings that the detent 31 will normally occupy a position with the tooth 46 located directly in advance of the respective stud 40 so that the ejector member 19 cannot be drawn forwardly to deliver the commodity which is contained within its front portion. However, if a coin of proper denomination engages the rear end portion 34 of the detent and depresses the 60 same, the detent will be swung about its pivot so that the finger 42 will engage the under side of the stud 40 and the ejector member 19 may then be drawn forwardly. Inasmuch as the specific details of the detent do not constitute a part of the present 70 invention, the specific functioning of the detent need not further be described. It is pertinent to remark, however, at this point that, as previously stated, the detent structure is duplicated at the two sides of the unit and 75 it will be obvious, therefore, that the ejector member 19 cannot be drawn forwardly to deliver one of the commodities unless the rear ends of both detents are depressed. When the ends of the detents are depressed 80 sufficient space will be provided at the lower or delivery end 35 of the coin passageway 36 to permit of delivery of any coin or coins within the said passageway, through the said end thereof into the coin receptacle upon 85 the bottom 11 thereof, the detents being maintained, however, in a position to retain the coins within the respective passageways until the studs 40 ride past the respective teeth 43, whereupon the weight of the coins 90 will effect downward tilting of the rear ends of the respective detents to the full limit and permit of the discharge of the coins into the coin receptacle.

The coin passageway 36 has a vertically 95 disposed coin inlet end 47 located adjacent the upper forward corner of the respective side member 15 of the unit 12 and this passageway, as previously explained, is defined by a channel formed in the outer face of 100 each side member 15 and by the respective face plate 37. By reference to Figure 5 of the drawings, it will be observed that the inner wall of the channel at the coin receiving end thereof, is disposed in a plane 105 inclined downwardly and inwardly from the plane of the outer face of the side member 15, so that the forward side wall of the channel is of gradually increasing width from the upper end of its said portion to 110 the lower end thereof. From the coin receiving end 47, the channel extends rearwardly and at a slight angle of downward inclination, as indicated by the numeral 48, and the bottom wall of this portion of the 115 channel, indicated by the numeral 49, is of a width equal substantially to the width of the lower end of the front wall of the portion 47 of the channel. The rear wall of the portion 47 of the channel and the 120 upper wall of the portion 48 of the channel are of substantially uniform width and of a width equivalent substantially to the width of the upper end of the front wall of the portion 47 of the channel. From the rear 125 end of the portion 48, the channel is extended substantially vertically downwardly to the delivery end 35 thereof, this portion of the channel being indicated by the numeral 50. The rear wall of this portion of 130

the channel, indicated by the numeral 51, is substantially vertical throughout its height and parallel to the rear edge of the side member 15, except that its lower end is 5 preferably inclined downwardly and rearwardly toward the said edge of the side member, as indicated by the numeral 52, for a purpose to be presently explained, and this wall is of a width equal substantially 10 to the width of the top wall of the portion 48 of the channel. The forward wall of the portion 50 of the channel, which wall is indicated by the numeral 53, is substantially parallel to the rear wall 51 of this portion of the channel and at its lower portion is inclined downwardly and rearwardly as at 54, the portion 54 opposing the portion 52 and being substantially parallel thereto. As previously stated, the bottom 15 wall 49 of the portion 48 of the channel is of substantially uniform width throughout its length but the inner wall of the channel from an approximately diagonal line intersecting the juncture of the bottom wall 49 of the portion 48 of the channel and the front wall 53 of the portion 50 thereof, and the approximate point of juncture of the upper wall of the portion 48 of the channel and the rear wall 51 of the said portion 20 50 of the channel, is gradually curved outwardly, as indicated by the numeral 55, throughout its surface area lying between the diagonal line referred to and a substantially horizontal line located slightly below 25 the juncture of the walls 49 and 53 of the channel, from which latter line, in a downward direction, the said inner wall of the channel 30 dips a plane substantially parallel to the plane of the outer face of the side member of the unit, this plane surface being continued below the delivery end 35 of the channel to a ledge portion 56 upon which the lower edge of the rear end 34 of the detent rests when the said end of the 35 detent is in full lowered position.

The plate 37 is disposed against the outer face of the respective side member 15 in marginal registration therewith and removably secured in place by means of screws or other suitable fastening devices 57, and it will be 40 evident at this point that said plate constitutes the outer wall of the coin passageway 36 and that the inner wall of the channel in the outer face of the respective side member 15 constitutes the inner wall of the said coin passageway. The plate 37 is formed with a rectangular opening indicated 45 by the numeral 58, which opening is defined by an upper wall 59 projecting a short distance below the upper wall of the portion 48 of the channel, an end wall 60 which extends substantially vertically and slightly rearwardly of the plane of the wall 53 of the portion 50 of the channel, another end wall 65 and a bottom wall, the opening being

downwardly and rearwardly inclined substantially to correspond with the inclination of the portion 48 of the channel. At the forward end of the opening, the material of the plate is pressed or otherwise formed 50 to provide a downwardly and inwardly inclined rest portion 61, the rear edge of which constitutes the forward end wall of the opening 58, indicated by the numeral 62. By reference to Figure 1 and the full and dotted 55 line illustration therein, it will be observed that the wall 62 of the opening 58 is located in a vertical plane slightly in advance of the plane of the rear wall of the coin receiving end of the channel in the respective 60 side member 15, and the purpose of thus locating the walls 60 and 62 of the opening will presently be made apparent. As stated, the coin rest 61 is inclined downwardly and inwardly and as will be observed by reference to Figure 3, it occupies an inclined plane parallel to the inner walls of the portions 47 and 48 of the coin conducting channel 36. In forming the plate to provide the rest 61, a flange 63 is provided at the lower 65 side of the opening 58 and constitutes the bottom wall thereof, and this flange extends inwardly over the bottom wall 49 of the portion 48 of the coin channel but has its free edge spaced from the plane of the inner wall of the portion 48 of said channel, as clearly shown in Figure 4 of the drawings, so as to provide a groove which is indicated by the numeral 64 and in which the lower peripheral portion of a coin passing 70 through the passageway will be guided as best shown in Figure 1 of the drawings, the position of the coin when first introduced being indicated by the reference character C'; the position of the coin when opposite 75 the opening 58 being represented by the reference character C''; and the coin within the coin receptacle being represented by the reference character C'''. By reference to Figure 4 of the drawings, it will be observed 80 that the free edge of the flange 63 at that end thereof next adjacent the end wall 60 of the opening 58 is slightly rounded, as indicated by the numeral 65 and that this rounded portion is located approximately 85 opposite the juncture of the walls 49 and 53 of the coin conducting channel 36.

It will be observed by reference to Figure 4 of the drawings, that the portion of the plate 37 in rear of the opening 58 is parallel to and spaced from the inner wall of the portion 50 of the coin conducting channel 36 so that this portion of the channel is of uniform breadth.

Coins are delivered to the coin receiving 125 end of the coin conducting channel by way of a coin chute 66 having a coin passageway 67 of dimensions to freely accommodate a coin of the predetermined denomination, the upper end of the chute being turned forwardly 130

and presented at the front 2 of the cabinet of the vending machine, and the lower end of the chute is of arcuate form, as indicated by the numeral 68, and the side walls of the chute rest upon the bottom wall 69 of a recess 70 in the outer face of the side member 15 and which recess accommodates a portion of the said lower end of the chute, the other portion of the said end of the chute being accommodated in an offset 71 formed in the upper forward corner of the face plate 37, the lower end of the passageway of the chute registering with the coin receiving slot thus formed at the upper end of the coin conducting passageway 36.

The foregoing description of the unit embodying the invention has been devoted to one side only of the said unit, as a matter of convenience in describing the construction thereof and the two sides are, in fact, identical except that the coin chute, coin passageway, and likewise the opening in the plate 37, are differently proportioned, so that a coin of one denomination may be deposited in the coin chute at one side of the unit and a coin of another proper denomination may be deposited in the coin chute at the other side of the unit. For example, one side of the unit may have its coin passageway proportioned to accommodate a dime or ten cent piece and the other side of the unit may have its coin passageway proportioned to accommodate a nickel or five cent piece, where the price of the commodity is fifteen cents. Inasmuch as in vending machines the coin slots into which the coins are initially introduced are of dimensions to accommodate a coin of a definite denomination, this will, of course, hold true in the present case and, therefore, the invention is concerned with the provision of means for preventing a coin of a diameter smaller than the coin of the proper denomination, acting upon the detent to actuate the same in any manner whatsoever. For example, let it be assumed that the coin passageway 36 shown in the drawings is proportioned to accommodate and provide for the proper passage of a five cent piece or nickel and that a coin of this denomination is deposited in the upper end of the chute 66. The coin will enter the receiving end 47 of the passageway and will be immediately canted, due to the inclination of the inner wall of this portion of the channel 36 and the inclination of the coin rest 61 and will momentarily rest against and move along the inner side of the said rest 61, the lower peripheral portion of the coin riding into the groove 64 and the upper peripheral portion of the coin riding against the inner face of the plate 37 immediately above the upper wall 59 of the opening 58, the said opening 58 being of a vertical dimension less than the diameter of the coin. This position of the coin is clearly shown in Figure 3 of the drawings, in dotted lines at the left of the said figure. The coin will then travel downwardly along the bottom wall 49 of the portion 48 of the coin conducting channel or passageway until it reaches the end 65 of the flange 63 and its forward peripheral portion rides against the outwardly curved surface 55 of the inner wall of the coin conducting channel, whereupon the coin will be caused to assume a vertical position and will descend through the portion 50 of the channel and strike the end 34 of the respective detent 31, depressing this end of the said detent until the upper side of the finger 42 engages the under side of the stud 40. If, prior to this time, or coincidently therewith, or subsequent thereto, a ten cent piece or dime is deposited in the coin chute at the other side of the unit, assuming, of course, that the respective coin passageway is proportioned to accommodate a coin of this denomination, the other detent will be likewise tripped and at this time the knob 28 may be grasped and, through the medium thereof, the ejector 19 may be slid forwardly against the tension of the spring 27, to deposit the commodity, which has been paid for onto the receiving tray 10, from which it may be removed by the purchaser, release of the knob 28 serving to return the ejector member 19 to its normal position, in which position it will be automatically locked by the two detents 31. There are car and bus tokens and foreign coins of little value which are of less diameter than a ten cent piece or dime and likewise, the penny or one cent piece is of less diameter than the nickel or five cent piece, and other tokens and foreign coins are of greater diameter than a dime but of less diameter than a nickel. Therefore, let it be assumed that an attempt is made, for example, to actuate the trip or detent by the introduction of a penny into the nickel coin chute and a car token into the dime chute. In neither instance will the corresponding detent be actuated for the reason, considering the attempted employment of a penny in lieu of a nickel, and that the penny is deposited in the nickel coin chute, it will enter the receiving end 47 of the coin passageway and will be canted as was the nickel in the previously described cycle of operation, but being of a diameter less than the coin which is of proper denomination, its upper peripheral portion will not engage with the inner face of the plate 37 immediately above the upper wall of the opening 58 but such peripheral portion will be located somewhat below the line of extent of this opening and inasmuch as the coin has been previously canted or tilted, and is afforded no support after it has moved past the coin rest 61, it will fall laterally through the opening 58 and between the unit into which it was deposited and the unit next adjacent thereto.

and will roll into the coin receptacle at the rear of the base of the machine. The same result will follow if a coin of a diameter less than that of a ten cent piece or dime is deposited in the coin chute at the other side of the unit, the opening 58 at the last mentioned side of the unit being, of course, of a height slightly less than the diameter of a dime and the coin passageway at said side 10 of the unit being, of course, proportioned throughout to readily accommodate the coin of the proper denomination. Should an attempt be made to obtain one of the commodities by depositing only one coin of proper 15 denomination as for example, a nickel in the nickel coin chute, the corresponding detent will, of course, be tripped, but inasmuch as it is essential that both detents be tripped before the ejector 19 can be actuated to deliver 20 the commodity, the nickel will merely remain in the coin passageway in which it has been deposited, the same resting upon the corresponding detent. If the one who has deposited the nickel would rather lose the same 25 than deposit a dime or other coin of proper denomination in the coin chute at the other side of the unit, the operativeness of the mechanism is in no way impaired for if a purchaser who is honest should deposit a 30 second nickel in the proper coin chute and a dime in the chute at the other side of the unit, then both detents will be tripped and both nickels and the dime will be collected in the coin receptacle, the ejector 19 being 35 at such time released for actuation to deliver the commodity. It will be evident from the foregoing that only such deposited coins as are of proper denomination can reach the detents of the units and that other coins, 40 tokens, or the like, will be delivered through the openings 58 in the side plates of the units without reaching the downwardly extending branch or portion 50 of the coin passageway. It will also be understood that 45 by restoring the coins of proper denomination from their canted position to an upright position, they will be conducted to the respective detents and strike the same directly edgewise to insure of positive actuation of 50 the detents. It will likewise be evident that the coin passageways of the unit cannot become clogged with coins to render the mechanism inoperative.

While each of the units embodies two of 55 the coin conducting passageways and the coin actuated detents, it will be readily understood that the principles involved are identical and that, therefore, the invention may be embodied in a unit having a single 60 coin conducting passageway and a single detent. It is observed that the several parts of the coinway are in substantially the same vertical plane, whereas the upper and lower portions 47 and 50 are disaligned, and connected by the intermediate portion 48 which

is slightly inclined to prevent a too rapid movement of an article less than the diameter of the prescribed coin from passing by the opening 58 without discharging there-through.

It will likewise be evident that various types of coin actuated detents may be employed as well as various constructions of ejectors for the commodities.

Having thus described the invention, what I claim is:

1. In a vending machine, a member having a coin channel formed in a side thereof and comprising disaligned upper and lower portions and an intermediate inclined connecting portion having its side wall tilted laterally, and a plate closing the open side of the coin channel and having the part opposite the inclined portion thereof deflected to present a wall substantially parallel with the laterally tilted wall of the channel, and having a portion of the deflected part cut away to provide an opening for the automatic discharge of an article of a diameter less than the diameter of the coin designed to traverse the coinway.

2. In a vending machine, a member having a coin channel formed in a side thereof and comprising receiving and delivery portions and an intermediate inclined portion connecting the receiving and delivery portions and having its side wall tilted laterally, and a plate closing the open side of the coin channel and having the part opposite the intermediate inclined portion of the channel deflected to present a wall paralleling the laterally tilted wall of the channel and a wall overlapping the bottom wall of the said intermediate inclined portion of the channel, and having a portion of the deflected part cut away to provide a side opening for the automatic discharge of an article of a diameter less than the diameter of the prescribed coin designed to traverse the coinway, marginal portions of the plate bordering upon the top and the bottom of the side opening defining grooves to receive the top and bottom edge portions of the prescribed coin and prevent its discharge.

3. In a coin controlled vending machine, a member provided in one face with an open-sided coin conducting passageway having a coin receiving end, a downwardly inclined portion, and a portion extending downwardly from the inclined portion, and a plate disposed against the side face of the member and closing the passageway and having an opening located opposite the inclined portion of the passageway, the inner wall of the coin receiving end and the inner wall of the downwardly inclined portion of the passageway being inclined upwardly toward the plate, the plate having a deflected portion opposing the said inclined inner wall of the coin receiving end of the passageway.

whereby to effect canting of a deposited coin in the direction of the said plate, the passageway being proportioned to accommodate a coin of a predetermined diameter, the upper wall of the opening in the plate projecting below the upper wall of the inclined portion of the passageway whereby to constitute a support for the upper peripheral portion of a canted coin of the predetermined diameter and support the same while passing the said opening.

15 4. In a coin controlled machine, a member provided in one face with an open-sided coin conducting passageway having a coin receiving end, a downwardly inclined portion, and a portion extending downwardly from the inclined portion and a plate disposed against the said face of the member and closing the passageway and having an opening located opposite the inclined portion of the passageway, the inner wall of the coin receiving end and the inner wall of the downwardly inclined portion of the passageway being inclined upwardly toward the plate, the plate having a deflected portion opposing the said inclined inner wall of the coin receiving end of the passageway whereby to effect canting of a deposited coin in the direction of the said plate, the passageway being proportioned to accommodate a coin of a predetermined diameter, the upper wall 35 of the opening in the plate projecting below the upper wall of the inclined portion of the passageway whereby to constitute a support for the upper peripheral portion of a canted coin of the predetermined diameter and support the same while passing the said opening and whereby a coin of smaller diameter will be deprived of support and delivered by gravity through the said opening, the plate

at the lower side of the opening having a flange projecting inwardly over the bottom 45 wall of the inclined portion of the passageway whereby to provide between its edge and the lower portion of the inner wall of the said inclined portion of the passageway a guiding channel for the lower peripheral 50 portion of the deposited coin, the said flange extending longitudinally of the said opening.

5. In a coin controlled vending machine, a member provided in one face with an open-sided coin conducting passageway having a 55 coin receiving end, a downwardly inclined portion, and a portion extending downwardly from the inclined portion, and a plate disposed against the said face of the member and closing the passageway and 60 having an opening located opposite the inclined portion of the passageway, the passageway being proportioned to accommodate a coin of a predetermined diameter, the upper wall of the opening in the plate projecting below the upper wall of the inclined portion of the passageway whereby to be engaged by the upper peripheral portion of such coin, the inner wall of the said inclined portion of the passageway being inclined upwardly toward the said plate whereby to 65 cant a deposited coin toward the said plate and whereby to effect gravity delivery of the coin through the opening in the event the coin is of less than the predetermined diameter, the inner wall of the inclined portion of the passageway and the inner wall of the downwardly extending portion of the passageway being merged on a gradual curve whereby to effect vertical disposition of a 80 coin of the predetermined diameter and to effect delivery of the said coin directly edge-wise.

In testimony whereof I affix my signature.

BENJAMIN L. FRY. [L.S.]
